(57) **CLAIM**

The ornamental design for a sole structure, as shown and described.

DESCRIPTION

FIG. 1 is a medial side and bottom view in perspective of a first embodiment of a sole structure showing my new design; FIG. 2 is a lateral side view thereof; FIG. 3 is a medial side view thereof; FIG. 4 is a top view thereof; FIG. 5 is a bottom view thereof; FIG. 6 is a front view thereof; and, FIG. 7 is a rear view thereof.

The sole structure illustrated in the drawings is a first embodiment showing a right-footed form of the sole structure. A second embodiment is for the left-footed form of the sole structure, which is a mirror image of the right-footed form, is not illustrated. The broken line illustration in the figures shows environmental structure and portions of the sole structure that form no part of the claimed design. The dot-dash line illustrations in the figures define the bounds of the claimed design and form no part thereof.
